UNITED STATES PATENT OFFICE.

CLEMENT F. DONART, OF VAN WERT, OHIO, ASSIGNOR TO LUVENIA DONART, OF VAN WERT, OHIO.

HAIR CURLER.

Application filed August 18, 1927. Serial No. 213,904.

This invention relates to improvements in hair curlers of a well known type used in permanently waving human hair. Such wavers or curlers commonly embody an electrically heated outer tube, a curling tube around which the hair is wound, said curling tube being receivable in the heating tube, and means for holding the two tubes in telescoped relation. The conventional holding means however is not as efficient as it should be and it does not in all instances serve to hold the curling tube so centered as to prevent contact of the hair with the heating tube. Hence, it is the object of my invention to provide new and improved centering and holding means for the curling tube.

With the foregoing and minor objects in view, the invention resides in the novel subject matter hereinafter described and claimed, the description being supplemented by the accompanying drawing.

Figure 1 is a perspective view of a hair curler improved in accordance with my invention, the curling tube being withdrawn from the heating tube.

Fig. 2 is a longitudinal section partly in elevation, the parts being related as shown in Fig. 1.

Fig. 3 is a sectional view showing the heating and curling tubes telescoped with each other.

Fig. 4 is a horizontal sectional view on line 4-4 of Fig. 2 showing more particularly the construction of the sleeve which is instrumental in anchoring the centering and holding device for the curling tube.

Fig. 5 is a perspective view of the sleeve just referred to and a portion of the centering and holding device.

Fig. 6 is a side elevation partly broken away and in section, showing the manner in which comparatively large curling tubes may be internally bushed for coaction with the centering and holding device.

In the drawing above briefly described, the preferred form of construction has been

illustrated and while this construction may be followed if desired, it is to be understood that within the scope of the invention as 50 claimed, numerous variations may be made.

The numeral 7 designates the heating tube having the usual electric heating means 8 and handle 9, and 10 denotes the curling tube which is insertible into said heating 55 tube as shown in Fig. 3, the lower end of this curling tube being provided with the conventional means 11 for engagement with the hair near the scalp, said means 11 commonly embodying a ratchet which permits 60 tightening of the hair after it has been wrapped about the tube.

Mounted centrally within the heating tube 7, is a centering and holding device 12 for the curling tube 10, said device being receivable within said tube 10 when the tubes 7 and 10 are telescoped as in Fig. 3. Thus the device 12 effectively holds the tube 10 centered within the tube 7 and prevents contact of the hair with said tube 7, over- 70 coming danger of burning such hair. Moreover, the device 12 effectively holds the curling tube 10 against accidental dropping from the heating tube 7. Attention is further invited to the fact that as the device 75 12 engages the inner side of the tube 10 rather than its outer side, there is no danger of said device contacting with the hair and thus producing undesirable formations upon the latter incident to the waving operation. 80

The device 12 is expandible and contractible to frictionally contact with the tube 10 and in the preferred form of construction, said device embodies two lengths of spring wire whose upper and lower portions may 85 be rather tightly twisted together as at 13 and 14, while the intermediate portions of the wire are outwardly bowed at intervals, as denoted at 15, thus providing yieldable means to frictionally contact with the 90 tube 10.

The wire structure so far described, forms a portion of a longitudinal shaft disposed in the heating tube 7 for holding and cen-

tering the curling tube 10. The remainder of this shaft may well be formed by a tube 16 secured around the wire ends 14, and a second tube 17 slidably surrounding the tube 16. Tube 17 forms the lower end of the shaft and it normally is so positioned at the lower end of the tube 7, as to be clearly visible, thus making it an easy matter to guide the shaft into the tube 10. Preferably, the tube 17 protrudes somewhat from the tube 7 as shown in Figs. 1 and 2, but as it would interfere with complete sliding of the tube 10 into tube 7, if permitted to remain in this projected position, said tube 17 has been slidably mounted upon the tube 16. Thus when this tube 17 contacts with the upper end of the means 11 as shown in Fig. 3, it merely slides upwardly upon the tube 16, thus permitting complete movement of tube 10 into tube 7. Downward movement of tube 17 may be limited in any desired manner, for instance by the coating stops 18—19 on the two tubes 16—17.

To facilitate guiding of the lower end of the tube centering and holding shaft into the tube 10, the upper end of the latter may be flared as at 20 if desired. Moreover, the lower end of the shaft may be given a substantially conical form as at 21 to assist in the guiding operation. Either of these formations 20—21 might be successfully used but preferably both are employed.

As customary, the tubes 10 are of different diameters, and if desired, relatively large tubes such as that shown in Fig. 6, may be provided with an internal lining or bushing 22 to insure tight frictional contact with the tube centering and holding device or shaft.

Any desired means may of course be employed for mounting the centering and holding device or shaft in the tube 7. In the present disclosure, a sheet metal sleeve 23 is received in the upper end of this tube 7 and may well have a projecting flange 24 abutting the upper edge of the latter. The lower end of this sleeve is provided with opposed inwardly stamped portions 25 through which a rivet or other pin 26 passes, and this member 26 is utilized to connect the upper end of the device or shaft 12 with the sleeve 23.

Preferably a plug 23^a of cork or other suitable material, fills the upper portion of sleeve 23, preventing undesirable radiation of heat which would otherwise take place.

By employing the novel construction herein shown and described or any analogous construction falling within the scope of the invention as claimed, a hair curler or waver is produced, which will be greatly advantageous over the conventional devices heretofore employed, particular attention being invited to the facts that the tube 10 is effectively held centered in the tube 7, said tube

10 is tightly held against accidental dropping from the tube 7, and the centering and holding means for said tube 10 does not contact with the outer side of the latter and hence can by no possibility come in contact with the hair being curled or waved.

I claim:

1. In a hair curler embodying a heating tube and a curling tube insertible into said heating tube; a centering device for said curling tube mounted centrally in said heating tube and insertible into said curling tube when the two tubes are telescoped.

2. In a hair curler embodying a heating tube and a curling tube insertible into said heating tube; an expandable and contractable centering device for said curling tube mounted centrally in said heating tube and insertible into said curling tube when the two tubes are telescoped, said device being adapted to contact with the inner side of the curling tube to retain the two tubes in assembled relation.

3. In a hair curler embodying a heating tube and a curling tube insertible into said heating tube; a centering shaft for said curling tube mounted centrally and longitudinally in said heating tube, said shaft being receivable in said curling tube when the two tubes are telescoped.

4. A structure as specified in claim 3; said shaft having a yieldable portion to frictionally contact with the inner side of the curling tube to retain the latter in the heating tube.

5. A structure as specified in claim 3; said shaft being expandible and contractable to contact with the inner side of the curling tube to retain the latter in the heating tube.

6. In a hair curler embodying a heating tube and a curling tube insertible into said heating tube; a centering shaft for said curling tube mounted centrally and longitudinally in said heating tube, and having one end portion exposed to view at the end of said heating tube which initially receives said curling tube, said shaft being receivable in said curling tube when the two tubes are telescoped.

7. A structure as specified in claim 6; said end portion of said shaft being slidably connected with the body portion of the latter for the purpose set forth.

8. A hair curler comprising a heating tube, a curling tube insertible into said heating tube, and a centering device for said curling tube mounted in said heating tube, said curling tube being provided with a flared end for guiding said centering device into said curling tube when the two tubes are telescoped.

9. A hair curler comprising a heating tube, a curling tube insertible into said heating tube, and a centering device for said

curling tube mounted in said heating tube and receivable in said curling tube when the two tubes are telescoped, said centering device having a substantially conical end for guiding it into said curling tube.

10. In a hair curler embodying a heating tube; a sleeve mounted stationarily in said tube and having opposed inwardly stamped side portions, a pin extending between and through said side portions, and a centering

device for a curling tube, said centering device being connected to said pin.

11. A structure as specified in claim 3; said shaft embodying a wire structure having outwardly bowed portions to frictionally 10 contact with the inner side of the curling tube.

In testimony whereof I have hereunto affixed my signature.

CLEMENT F. DONART.
